(57) **CLAIM**

The ornamental design for a forehead heat protector as shown and described.

DESCRIPTION

FIG. 1 is a perspective view of a forehead heat protector; FIG. 2 is a front elevation view thereof; FIG. 3 is a back elevation view thereof; FIG. 4 is a right side view thereof; FIG. 5 is a left side view thereof; FIG. 6 is a top view thereof; FIG. 7 is a bottom plan view thereof; and, FIG. 8 is a front elevation view thereof, shown in an environment of use as worn on a person's forehead. The broken lines showing of a human head in FIG. 8 represent environmental subject matter and form no part of the claimed design.

1 Claim, 4 Drawing Sheets
